REISSUED

UNITED STATES PATENT OFFICE.

WILLIAM S. BIEL, OF LOS ANGELES, CALIFORNIA.

DESIGN FOR A BEDSTEAD.

49,793.

Specification for Design.

Patented Oct. 24, 1916.

Application filed July 21, 1916. Serial No. 110,603. Term of patent 3½ years.

To all whom it may concern:

Be it known that I, WILLIAM S. BIEL, a citizen of the United States, residing at Los Angeles, in the county of Los Angeles and State of California, have invented a new, original, and ornamental Design for Bedsteads, of which the following is a specification, reference being had to the accompanying drawing, forming a part thereof.

The figure is a perspective view of a bedstead, showing my new design.

I claim:

The ornamental design for a bedstead, as shown.

WILLIAM S. BIEL.

Witnesses:

STELLA M. CHAMBERS,
FREDERICK B. FOOTE.
